INVENTOR
George Racz.
BY Oscar Geer
his ATTORNEY

UNITED STATES PATENT OFFICE.

GEORGE RACE, OF CHICAGO, ILLINOIS.

WINDOW-CLEANER.

1,309,302.

Specification of Letters Patent. Patented July 8, 1919.

Application filed June 3, 1918. Serial No. 233,926.

To all whom it may concern:

Be it known that I, George Race, a subject of the King of Hungary, residing at Chicago, county of Cook, and State of Illinois, have invented certain new and useful Improvements in Window-Cleaners, of which the following is a specification.

This invention relates to improvements in devices for cleaning windows, and has as its special object the provision of means whereby a window may be cleaned from the interior of the room and upon either side of the window pane in an easy and convenient manner.

15 A further object is to provide means whereby a supply of water may be sprayed so as to thoroughly clean and rinse the window pane as the device is actuated thereagainst.

20 Another object is to provide means whereby the dirty water enters a tank provided for that purpose and finally, to provide a window cleaner having a resilient mop to which is attached flexible tubes so that the 25 same may be handled in an easy and efficient manner.

These and other like objects are attained by the novel construction and combination of parts hereinafter described and shown 30 in the accompanying drawing, forming a material part of this disclosure, and in which:—

Figure 1 shows the device in side elevation, the window being shown in section.

35 Fig. 2 is a perspective view showing the complete apparatus, and

Fig. 3 is an enlarged fragmentary vertical sectional view, taken through the applicator, attached pipe and resilient mop.

40 In the drawings, the numeral 10 indicates an ordinary window frame in which are slidably mounted upper and lower sashes respectively 11 and 12, the window and its frame being of a conventional type of construction.

45 The apparatus consists of a platform or base 15, upon which are secured two tanks 16 and 18, provided with removable covers. Engaged with the supply tank 16 is a pipe 19, connected with a hand pump 20, secured to the platform 15 and provided with an

operating handle 21 of the usual type of construction.

Extending into the supply tank 16 is a flexible hose 23, connected by the fittings 24 with a transverse pipe 25 containing a plurality of perforations 26, the perforate pipe resting in the lower inner surface of the semi-circular, contacting mop or applicator 28, made of rubber or like flexible material, so that both of its parallel edges may make contact with the object to be cleared. Also engaged with the lower portion of the element 28 is another like fitting 29, from which extends a flexible hose 30, connecting 65 with the drain tank 18, the arrangement being such that water gathered by the applicator or mop 28 is caused to pass down through the pipe 30 into the tank if the applicator, which is closed at its ends, is inclined toward the side where said pipe is located.

Secured centrally to the applicator 28, between the fittings 24 and 29, is a support bracket 32, containing a cylindrical axial 75 opening 33 and formed with a flanged lower surface 34, in which is secured the ends of tensional springs 35, their opposite ends being fixed on arms 37, attached to the support rod 38, the upper end of which is 80 slidably received within the axial opening 33, thus providing for a certain amount of resilience in the mounting of the applicator.

The support rod 38 is bent at its lower end, and formed with a substantially horizontal bar 39, terminating in a T shaped handle 40, adapted to be grasped by the hand of an operator, who, due to the form of the handle, is able to press the applicator tightly against the surface of the window 90 pane to be cleaned, while the pump 20 forces a stream of water against the window so as to thoroughly cleanse the same, the action of the edges of the mop being equivalent to that of a hand pressed squeegee as will be 95 obvious.

The construction and operation of the implement are believed to be apparent from the disclosure herein made, and thus having described my invention, what I claim as 100 new and desire to secure by Letters Patent, is.

In a window cleaning apparatus of the character described, the combination of an applicator with two flexible hoses adapted to be connected to sockets of the applicator 5 and to a drain and supply tank, and a handle, a bracket between said sockets and a rod secured to said handle and slidably en-

gaging said bracket, and tensional springs connected to said socket and an arm of said rod for resiliently controlling said sliding movement.

In testimony whereof I have affixed my signature.

GEORGE RACZ.
